T. E. POTTS

BURNER

Filed April 7, 1924

INVENTOR.

THOMAS E. POTTS,

By: Otto H. Kueger,
his Atty.

UNITED STATES PATENT OFFICE.

THOMAS E. POTTS, OF LOS ANGELES, CALIFORNIA.

BURNER.

Application filed April 7, 1924. Serial No. 704,705.

To all whom it may concern:

Be it known that I, THOMAS E. POTTS, a citizen of the United States, residing at Los Angeles, in the county of Los Angeles and 5 State of California, have invented a new and useful Burner, of which the following is a specification.

This invention relates to devices used in stoves and furnaces for generating heat.

10 One of the objects of this invention is to provide a device with an overhead air supply.

Another object is to provide a device in which and through which gaseous as well as 15 liquid fuel can be handled, an overhead air supply being arranged so that the air passes equally well over impassing gaseous and liquid fuel.

Another object is to provide a device with 20 fully sealed-off fuel supply connections, by which fuel can be injected into the device before air can mix with the fuel.

Another object is to provide proper fuel and air passage controlling and adjusting 25 means.

Other objects will appear from the following description and appended claims as well as from the accompanying drawing, in which—

30 Fig. 1 is a longitudinal sectional view of a burner-box of a simple construction, illustrating gaseous and liquid fuel connections, and showing removable and adjustable shutters and baffles.

35 Fig. 2 is a front elevation of the box in Fig. 1, having the front and top shutter removed.

Fig. 3 is a fragmentary detail sectional view on line 3—3 of Fig. 2, illustrating a 40 needle-valve for a gas-jet.

Fig. 4 is a top plan view of the adjustable top shutter, in partly closed position.

Fig. 5 is a fragmentary diagrammatic illustration of an arrangement of a device 45 within a range or stove, including a chimney.

The common gas burners for stoves and ranges are generally designed so that gas is discharged into a jet-like and tubular member through which air is drawn into the 50 burner together with the gas-injection.

Hotels, restaurants, and other establishments, catering to large numbers of people have special stoves and ranges with proportionally large burners, whether gas or liquid 55 fuel is used. Independent burners for gas

and other burners for liquid fuel are very often provided to enable such places to furnish meals regardless of the lack of fuel, either, gaseous or liquid fuel. 60

Burners, designed for burning liquid fuel are generally not suitable for burning gas.

A common type of burner for burning liquid fuel is illustrated in Figs. 1, 2 and 5, in its general outline, though in these particular illustrations the burner is designed to burn gaseous or liquid fuel. In this type of burners, the necessary air is allowed to enter the burner from the top or over the in-passing fuel, to mix with the fuel within 70 the burner, the in-passing fuel being directed in the general line of the arrow 6, while the in-passing air is directed in the general line of the arrow 7 from overhead in relation to the fuel, see Fig. 1. 75 In burning liquid fuel, the fuel is generally injected into a burner under pressure, but the main pan 8 serves to hold the fuel in its liquid state, while the air passes over this fuel in the pan. The liquid fuel is passed 80 into the burner by way of the tube 9, to be controlled by a valve in the pipe line 9, the valve being not shown in the drawing, since any common valve may be used for this purpose. The liquid fuel is ignited in the pan 85 8, to generate the required heat for stoves, furnaces, and ranges. The burning fuel normally draws in air through the overhead air funnel 10.

To make this common-type liquid-fuel burner useful for burning gaseous fuel, fundamental changes have to be made. The Figs. 1, 2 and 5 illustrate a device designed to allow the use of gaseous and liquid fuels. The termination 11 of the supply connection 90 9 for the liquid fuel is similarly positioned near the front edge or end 12 of the burner pan 8 as the termination 13 of the gas supply, the gas discharge or termination being illustrated in Fig. 3, while the liquid fuel 95 discharge or termination is illustrated in Fig. 1.

A body in form of a manifold is provided at the front end of the burner plate or pan 8, as illustrated in Figs. 1, 2 and 3, for supplying gas to a required number of gas discharge outlets. Each of the gas discharge outlets 13 is preferably provided with an adjustable needle-valve 15. 16 designates a main gas-supplying connection, as indicated in Fig. 2, which may be provided with a main controlling valve, not shown in the 100 105 110

drawing, as well as pointed out with reference to the main supplying connection 9 for the liquid fuel.

Either gaseous or liquid fuel may in this manner be discharged into the burner, to mix with air within the burner.

However, gas is generally not discharged with sufficient pressure as that it would draw air into a burner of this type. A chimney 17 is therefore preferably provided, as indicated in Fig. 5, or, in other words, a burner of this type is preferably used in stoves, furnaces, or ranges that have a chimney. A portion of a range or stove is indicated at 18 in Fig. 5, illustrating the combination and arrangement of a burner (roughly outlined at 19) within the range, and a chimney, extending upwardly from the range.

Plates 20 and 21 are preferably provided over the top of the air funnel 10. These plates are provided with perforations to come into aligned position when fully open while the one plate may be shifted in relation to the other plate to allow an adjusting of the air passage into the burner through the funnel, as illustrated in Fig. 4.

The partition or baffle plate 22 is made removable and thereby adjustable, so that the space between the baffle 22 and the pan 8 may be maintained in proper proportion to the particular burner.

The front shutter 23 is also made removable. This is for the purpose of providing a simple casting, and for making the burner easily accessible. The front shutter 23 and the top plates 20 and 21 are not shown in Fig. 2, so that the baffle 22 may be seen through the open front of the burner.

Of course, it is immaterial, whether the gas-manifold is made integral with the burner or detachable, the important point being that the manifold is designed so that the connection for the liquid fuel can be provided to receive overhead air supply equally well with the gas connections.

Having thus described my invention, I claim:

1. In a burner of the class described, a pan having front, rear, and side walls projecting upwardly from the bottom plate, a conduit for liquid fuel terminating within the front wall of the pan, a gas manifold disposed along the front wall of the pan

and having independent discharge outlets 55 extending through the said front wall of the pan adjacent of the conduit for the liquid fuel, and overhead air supplying means over the front end of the pan and over the fuel discharge.

2. In a burner of the class described, a pan having front, rear, and side walls projecting upwardly from the bottom plate of the pan, means by which liquid fuel can be passed into the pan through the front wall of the pan, and a gas manifold disposed along the front wall and having a curved portion disposed at a point where the liquid fuel is to be passed through the front wall and having independent discharge outlets extending through the said front wall at the level near the point where the liquid fuel is passed into the pan.

3. In a burner of the class described, a pan having front, rear, and side walls projecting upwardly from the bottom plate of the pan, a gas manifold disposed along the front wall having discharge outlets extending through the said front wall, and a conduit for liquid fuel extending through the front wall in nearly the same level with the outlets of the gas manifold.

4. In a burner of the class described, a pan having front, rear, and side walls projecting upwardly from the bottom plate of the pan, a gas manifold disposed along the front wall having discharge outlets extending through the said front wall and having a curved portion by which the said front wall is left free of the manifold at a point 85 in the level of the said outlets, a conduit for liquid fuel extending through the front wall in nearly the same level with the said outlets at the said point where the front wall is left free of the manifold, a center baffle plate removable disposed between the said side walls of the pan with its lower edge spaced above the bottom of the pan and spaced from the said front wall, and air controlling means over the front end of 90 the pan including the front wall with the side walls and the center baffle plate to form an over head air control at an equal distance over the said outlets and conduit.

In testimony that I claim the foregoing 105 as my invention I have signed my name.

THOMAS E. POTTS.
